Primary Examiner—Martie Thompson
Attorney, Agent, or Firm—Wallenstein, Wagner & Hattis, Ltd.[57] **CLAIM**

The ornamental design for a combined writing instrument holder and flashlight, as shown and described.

DESCRIPTION

FIG. 1 is a bottom plan view of a combined writing instrument holder and flashlight showing my new design;

FIG. 2 is a side elevational view;

FIG. 3 is an end elevational view;

FIG. 4 is a side elevational view of the side opposite that shown in FIG. 2;

FIG. 5 is a top plan view;

FIG. 6 is an end elevational view of the end not shown in FIG. 3;

FIG. 7 is a top perspective view; and,

FIG. 8 is a top perspective view thereof with the flashlight rotated to an operable position.
